METHOD OF CONTROLLING THE PICK-UP
AND DROP-AWAY VALUES OF MERCURY
SWITCH RELAYSCarl H. Larson, Elkhart, Ind., assignor to The
Adlake Company, a corporation of Illinois

Application August 24, 1935, Serial No. 37,723

9 Claims. (CL 200—112)

Electromagnetic relays have a great variety of uses. The operating characteristics of any particular relay are determined by the power available and the function that the relay is to perform. 5 In some cases, the relay is required to operate within relatively narrow ranges of voltage changes; in other cases, a relatively large difference between pickup and drop away values is desirable. 10 To a limited extent, the desired operating characteristics may be obtained by adjusting the air gaps in the iron circuit, by increasing or decreasing the power consumption of the relay, and by controlling the conditions under which 15 the relay is made to operate; but there are limiting factors which sometimes make it very difficult to obtain specified operating characteristics.

In electro-mechanical relays it is necessary to establish a minimum air gap in order to guard 20 against relay failure due to remanence in the iron circuit. The air gap, as thus determined, necessarily limits the sensitivity of the relay. Furthermore, it is necessary to employ sufficient power in electro-mechanical relays to overcome the effect of contact resistance. 25

In mercury switch relays, however, of the type disclosed in Larson, Patent No. 1,967,247, issued July 24, 1934, there is no contact resistance (at least the contact resistance is infinitesimal), and 30 the minimum air gap is furnished by the glass envelope which contains the armature. Hence, it adapts itself more readily to unusual design requirements.

I have discovered that the pickup and drop 35 away characteristics of mercury displacement relays may be controlled within wide limits by giving due consideration to the shape of the intermittently immersed electrode and/or the shape and material of the insulating sleeve which surrounds that electrode for a portion of its height.

The primary object of this invention, therefore, 40 is to determine how the shape of the intermittently immersed electrode and the material of which it is composed affect the pickup and drop away values of the relay.

Further and other objects and advantages will 45 be apparent as the disclosure proceeds and the description is read of the accompanying drawing of which

10 Figs. 1 and 2 are views which will be used to explain the type of relay to which the invention is particularly applicable;

Figs. 3 to 13 inclusive are fragmentary views of 50 various forms of central electrodes; and

15 Fig. 14 is a chart showing how the electrodes

of Figs. 3 to 13 inclusive affect the pick up and drop away values of the relay.

At the outset it should be specifically understood that the illustrations and descriptions of specific forms of electrodes are for the purpose 5 of complying with Section 4888 of the Revised Statutes and that the invention is not limited to these forms or any of them unless required by the prior art.

The utility of this invention is illustrated by its 10 application to a relay of the mercury displacement type which comprises a relay coil 20, an iron circuit 21 and a mercury switch 22. The switch 22 comprises a glass envelope 23 containing a quantity of mercury 24 and through the 15 base of the envelope electrodes 25 and 26 are sealed. Electrode 25 is covered for a portion of its length by an insulating sleeve 27 that is fused to both the electrode 25 and the switch envelope. Preferably the switch envelope 23 and 20 the insulating sleeve 27 are made of high grade 25 borosilicate glass, as for example, that disclosed in Weintraub, Patent No. 1,154,081, issued Sept. 21, 1915.

A displacer 28 of iron or other suitable magnetic material responds to the flux set up by the 30 coil 20 and displaces more or less mercury, depending upon the state of energization of the coil 20. As shown in Fig. 1, the coil 20 is de-energized and the mercury level is such that the 35 bared end 29 of the central electrode 25 is out of contact with the mercury and hence the circuit through the electrodes 25 and 26 is open. When the coil is energized, the displacer is drawn 40 downwardly within the switch envelope as shown 35 in Fig. 2, and a sufficient quantity of mercury is displaced to bridge the electrodes 25 and 26.

For dependable operation the mercury is purified prior to its insertion in the switch envelope, and before the envelope is sealed off at 36, the 45 entire envelope is evacuated of air (the mercury being heated during the process to drive out included and occluded gases), and then filled with an inert gas such as helium, hydrogen, or the like.

Preferably the displacer 28 is restrained by a spring 31 (when the coil 20 is de-energized) to a position within the switch envelope that is somewhat below its position of floating equilibrium. 50 The purpose of this is to make the relay more sensitive and to hold to a minimum the power that is required to operate the relay.

The iron circuit 21 is of no particular importance to this disclosure and suffice to say that it 55

may be of the type disclosed in Larson, Patent No. 1,967,951, issued July 24, 1934.

Before describing in detail the illustrative embodiments of the invention, it may be helpful to analyze briefly the theory which is believed to underlie the present invention, although all theoretical discussions in this specification are to be construed not as defining a mode of operation, but merely as a possible explanation of certain physical or electrical phenomena known to exist.

Let us assume that the plunger 28 is in the position shown in Fig. 1 and that sufficient voltage is applied to the coil 20 to bring the mercury level approximately to the top of the insulating sleeve 27. Since mercury has a relatively high surface tension (of the order of 500 dynes per square centimeter) it is actually possible to have the mercury level in the switch above the top of the insulating sleeve 27 without establishing contact between the bared end 29 of the electrode 25 and the mercury fill. The force that holds the mercury away from the bared end 29 is a function of the surface tension of the mercury, the area of contact between the sleeve 27 and the mercury, and the coefficient of friction of the material constituting the sleeve 27. Since it is not practical to change the surface tension of mercury by the addition of chemicals, I control the pickup and drop away values of the relay by varying the area of contact between the mercury and the sleeve, and/or the bared end 29 of the electrode, or by varying the material of which the sleeve 27 is composed. The variations in shape and/or material may have the effect of retarding the movement of mercury toward circuit closing position, or impede the breaking of the circuit, or both.

Since industrial applications of relays may call for a spread in pickup and drop away values from a very small percentage of the normal operating voltage up to as high as 60 percent, I have shown in Figs. 3 to 13 inclusive, illustrative forms of electrodes which are capable of effecting differences in pickup and drop away values ranging from substantially equal pickup and drop away values to a spread of approximately 25 percent of the normal operating voltage (the electrode of Fig. 3 having substantially equal pickup and drop away values and those in the subsequent figures having progressively increasing differences in pickup and drop away values, as shown in the chart of Fig. 14).

In Fig. 3 the bared end of the electrode 25 is bent over to one side of the sleeve 27 and the tip of the bared end is pointed as indicated at 32. The pickup and drop away values of a switch using this type of electrode are substantially equal because the area of contact between the electrode 25 and the mercury at the moment when the circuit is broken is held to a minimum and the effect of surface tension is correspondingly small.

The electrode of Fig. 4 differs from that shown in Fig. 3 in that the tip of the electrode is rounded as indicated at 33, thereby slightly increasing the effective area of contact correspondingly increasing the difference between the pickup and drop away values of the relay.

The electrode of Fig. 5 differs from that in Fig. 4 by having the bared end of the electrode squared off as at Fig. 4 and by referring to Fig. 14, it will be seen that this electrode raises the pickup and drop away spread to approximately 5 percent.

It will be noticed that when the bared end of the electrode is bent over to one side, the insu-

lated portion of the electrode is set to one side so that the downwardly projecting bared end of the electrode may lie on the longitudinal axis of the switch. The purpose of this is to have the making and breaking of the electrical circuit take place at the exact center of the switch so as to maintain the desired operating characteristics even though the switch envelope may be slightly tilted with respect to the vertical axis.

The electrode of Fig. 6 is the same as that shown in the assembled relay of Fig. 1. Here the bared end of the electrode projects upwardly from the sleeve 27 and the mercury in making contact with the bared end of the electrode must ride over the shoulder 35 of the insulating sleeve 27.

In Fig. 7 a small bead 36 is formed on the end of the sleeve 27 and this impedes the flow of mercury to the electrode when the circuit is being closed.

In the electrode shown in Fig. 8, a sleeve 37 of ceramic material such as Alundum, a product of the Norton Company, Worcester, Massachusetts, is fused to the end of the sleeve 27. It has been found that Alundum and similar materials, when used in this manner, increase the spread in pickup and drop away values, presumably because the material is highly refractory and any arcing that occurs when the circuit through the switch is opened has little or no effect in disintegrating the portion of the refractory sleeve over which the arc forms. When the electrode is formed so that the arcing takes place over the shoulder 35 of the glass sleeve 27 (as shown in Fig. 6), the shoulder is quickly rounded to the form shown in Fig. 6, with the result that less mercury need be displaced in order to complete the electrical circuit through the electrodes.

In Figs. 9 to 11 inclusive, a glass or ceramic cup 38 is fused to the end of the insulating sleeve 27 so that the end of the electrode 25 is exposed within the cup. The cup is normally filled with mercury as shown at 39 so that when the switch displacer is lowered, the circuit through the switch is completed over the edge 40 of the cup, this edge preferably being on the longitudinal axis of the switch. I have found that I can control the spread in pickup and drop away values when using a cup of this type by varying the angle at which the cup is cut, for when the cup is cut off at a steep angle, the difference in pickup and drop away values is less than when the cup is cut off at a smaller angle.

In Fig. 12 the cup on the end of the electrode 25 is cut away on two sides which obviously increases the spread between the pickup and drop away values.

In Fig. 13 the cup electrode is squared off so that when the circuit is broken, there is a relatively large area of contact between the two bodies of mercury.

The illustrative embodiments of the invention described above and the explanations that have been made with reference to their effect on the pickup and drop away values in the relay make it clear that greater differences in pickup and drop away values may be obtained by corresponding changes in the shape of the protective sleeve around the intermittently immersed electrode and similar changes in the material; for example, the thickness of the ceramic cup in the cup electrode shown in Fig. 13 may be increased to produce a corresponding increase in the difference between the pickup and drop away values.

Obviously the impedance to the mercury flow

may be accomplished by means other than the sleeve surrounding the central electrode. All that is necessary is that the effect of the surface tension of the mercury in the vicinity of the 5 intermittently immersed electrode be made to correspond with the span of pickup and drop away values desired.

Throughout the specification and claims, the 10 expressions "pickup value" and "drop away value" have been frequently used, and the following explanation will serve to indicate what is meant by these expressions.

The pickup value of a relay is the minimum 15 voltage which must be applied to a relay coil in order to operate the relay (i. e. open the contacts in a back contact relay, or close the contacts in a front contact relay). If a lesser voltage is applied to the coil, the relay will not operate.

20 The drop away value of a relay is the minimum voltage which will sustain the relay in its energized position (i. e. keep the contacts open in a back contact relay or keep them closed in a front contact relay). If the voltage falls below 25 the drop away value, the condition of the electrical circuit through the contacts will change.

Both pickup and drop away values are critical, particularly in a mercury switch relay of the type herein disclosed.

30 To illustrate the use of the terms, let it be supposed that the coil 20 in Fig. 1 is connected to a suitable source of electromotive force, and that a rheostat and voltmeter have been placed in the circuit in order that the voltage across the 35 coil may be varied at will, and indicated.

Starting with a zero voltage across the coil and gradually increasing the voltage, it will be observed that when the voltage has reached some predetermined value, for example, two volts, the 40 spring 31 will have been relieved of its compression and subsequent increases of voltage will produce a proportional downward movement of the displacer. As the voltage across the coil is increased, the mercury level within the switch gradually rises due to the displacement action of the armature 28, and at some critical voltage (pickup value of the relay), say 5 volts, the mercury level 45 will finally reach the bared end 29 of the electrode 25 and close the electrical circuit between the electrodes 25 and 26. Obviously after the contacts have been closed, further increases in the voltage across the coil will not change the closed condition of the electrical circuit through the contacts, although the armature may be drawn 50 farther down into the mercury.

Now let it be supposed that in the case above, after the voltage across the coil had been increased up to 7 or 8 volts the rheostat is operated to progressively decrease the voltage 60 across the coil. For each successive decrease in voltage, the armature 28 moves upwardly proportionately, and the mercury level falls a corresponding amount. When the voltage is reduced to 5 volts the armature 28 occupies exactly the same position that it occupied at that voltage when the voltage was being increased, but due to the surface tension of the mercury, the 65 mercury column will not break away from the exposed end 29 of the electrode 25 until there has been a further reduction in voltage. For the type of electrode shown in Fig. 1, the break in the electrical circuit will come when the voltage is reduced to approximately 4.6 volts. In the 70 illustration given above, the spread between the 75

pickup and drop away values is the difference between 5 and 4.6, or $\frac{1}{8}$ ths of a volt.

If an electrode, such as shown in Fig. 13 had been used in place of the one shown in Fig. 1, the voltage across the coil, under the same circumstances, would have had to be reduced to approximately 3.8 volts before the circuit through the electrodes 25 and 26 would open.

I claim as my invention:

1. A method of controlling the span between 10 the pickup and drop away values of a mercury displacement relay of the type in which a quantity of mercury is adapted to be manipulated in and out of contact with an electrode, said method consisting in forming the electrode of such shape 15 that the desired span will be obtained through the effect of the surface tension of the mercury when contacting the electrode.

2. A method of controlling the span between 20 the pickup and drop away values of a mercury displacement relay of the type in which a quantity of mercury is adapted to be manipulated in and out of contact with a conducting surface of an electrode member having an insulating sleeve, 25 said method consisting in forming said sleeve in such a manner that the desired span will be obtained through the effect of the surface tension of the mercury in contact therewith.

3. A method of controlling the span between the 30 pickup and drop away values of a mercury displacement relay of the type in which a quantity of mercury is adapted to be manipulated in and out of contact with a conducting surface of an electrode member having an insulating sleeve, 35 said method consisting in so forming said sleeve as to shape and material that the desired span will be obtained through the effect of the surface tension of the mercury in contact with said sleeve.

4. A method of controlling the span between 40 the pickup and drop away values of a mercury displacement relay of the type in which a quantity of mercury is adapted to be manipulated in and out of contact with a conducting surface of an electrode member having an insulating sleeve, 45 said method consisting in so forming said sleeve as to its shape that the desired span will be obtained through the effect of the surface tension of the mercury in contact with said sleeve.

5. A method of controlling the span between 50 the pickup and drop away values of a mercury displacement relay of the type in which a quantity of mercury is adapted to be manipulated in and out of contact with a conducting surface of an electrode member having an insulating sleeve, 55 said method consisting in so forming said sleeve as to its material that the desired span will be obtained through the effect of the surface tension of the mercury in contact with said sleeve.

6. A method of controlling the span between 60 the pickup and drop away values of a mercury displacement relay of the type in which a quantity of mercury is adapted to be manipulated in and out of contact with a conducting surface of an electrode member, said method consisting in 65 selecting an electrode member to produce a surface tension effect of mercury in contact with said member capable of producing the desired span.

7. A method of controlling the span between 70 the pickup and drop away values of a mercury displacement relay of the type in which a quantity of mercury is adapted to be manipulated in and out of contact with a conducting surface of an electrode member, said method consisting in selecting means to produce a surface tension effect 75

of mercury in contact with said member capable of producing the desired span.

8. A method of controlling the span between the pickup and drop away values of a mercury displacement relay of the type in which a quantity of mercury is adapted to be manipulated in and out of contact with a conducting surface of an electrode member, said method consisting in selecting means to produce a surface tension effect of mercury in the vicinity of said member capable of producing the desired span.

9. A method of controlling the span between the pickup and drop away values of a mercury displacement relay of the type in which a quantity of mercury is adapted to be manipulated in and out of contact with a conducting surface of an electrode member, said method consisting in selecting means to produce a surface tension effect of mercury surrounding said member capable of producing the desired span. 5

10

CARL H. LARSON.
